Primary Examiner — Katrina A Betton(74) *Attorney, Agent, or Firm* — Dinsmore & Shohl LLP(57) **CLAIM**

The ornamental design for a travel trailer, as shown and described.

DESCRIPTION

FIG. 1 is a front perspective view of a travel trailer illustrating our new design;

FIG. 2 is a rear perspective view of the design of FIG. 1;

FIG. 3 is a front view of the design of FIG. 1;

FIG. 4 is rear view of the design of FIG. 1;

FIG. 5 is a side view of the design of FIG. 1;

FIG. 6 is another side view of the design of FIG. 1;

FIG. 7 is a top view of the design of FIG. 1; and,

FIG. 8 is a bottom view of the design of FIG. 1.

The broken lines represent portions of the structure that form no part of the claim.
